FRANK R. ZUMBRO AND FRANCIS SHENTON, OF WAYNESBORO, PENNSYLVANIA,
ASSIGNORS TO FRICK COMPANY, OF WAYNESBORO, PENNSYLVANIA, A CORPORATION OF PENNSYLVANIA

SWITCH

Application filed April 24, 1928. Serial No. 272,497.

Our invention relates to a quick acting or snap switch adapted to be used in conjunction with single phase split phase induction motors, or the like, and it is an object of the 5 invention to provide a simple and positively acting switch, all as will be hereinafter more particularly described.

Referring to the accompanying drawings which are made a part hereof and on which 10 similar reference characters indicate similar parts,

Figure 1 is a side elevation of a switch illustrating one application of our invention,

Figure 2, a top plan view, and

15 Figure 3, a fragmentary end elevation of the mercury tubes.

In the drawings reference character 12 indicates a solenoid and 13 a pair of mercury tube switches which are adapted to be controlled thereby. The mercury tube switches 20 13 are mounted on a rocker arm 14 operating in conjunction with an arm 15 connected with the core of the solenoid 12. The mercury tubes 13 each has one pole, the front pole as 25 shown in Figure 1, in series circuit with the starting winding and the other pole—the rear one as shown in said figure in parallel or shunt circuit to the solenoid 12. We preferably use mercury tube switches each having 30 in one end contacts 16 and 17 projecting into the tube and adapted when the tube is tilted to cause the mercury to flow to the end of the tube in which the contacts are located and bridge the contacts. However if desired other 35 switches may be used.

The rocker arm 14 which supports the mercury tubes is pivotally mounted on the base 44 and to said base is also pivoted at the same point the bifurcated end of the arm 15. The 40 rocker arm 14 is mounted in the bifurcation in the end of the arm 15, and is provided with an arrow head or bevel faced cam 18, and said arms are provided with opposed slots 19 in which are journaled the extremities of a 45 roller 20. A coil spring is disposed around the forward end of the bar 15 and engages the roller 20, the opposite end of the spring being adjustably held against longitudinal movement by lock nuts 25. This construction 50 causes the roller 20 to bear on either the

upper or lower face of the cam 18 and maintain the mercury tubes tilted in one extreme position for completing the circuits and in the other extreme position for breaking the circuits.

In operation when the bar 15 is moved downward under the influence of the solenoid the roller 19 will ride over the apex of the cam 18 and throw the rocker arm 14 upward with a snap action. When the electromagnet 55 is not energized in order to maintain the parts in the position shown in Figure 1 we provide a spring 27 which will normally hold the parts as shown, and will permit the core of the electromagnet to be attracted, but will return 60 the parts to the position shown as soon as the core is released.

It will be obvious to those skilled in the art that various changes may be made in our device without departing from the spirit of 70 the invention, and we, therefore, do not limit ourselves to what is shown in the drawings and described in the specification, but only as set forth in the appended claims.

Having thus fully described our said invention, what we claim as new and desire to 75 secure by Letters Patent is:

1. A snap switch comprising a bar pivotally supported at one end and having its opposite end resiliently supported and connected with the core of an electromagnet, said bar having 80 its pivotally mounted end bifurcated, a roller resiliently supported in the bifurcation of said bar, a spring engaging said roller, an arm pivotally mounted on the same support 85 as the pivoted end of said bar and having upper and lower cam faces at one end engaging said roller, a mercury tube supported on said arm and having contacts at one end thereof, said roller being adapted to ride 90 from one face over the apex and onto the other cam face of said bar and operate said switch with a snap action upon the energizing or deenergizing of the electromagnet, substantially as set forth.

2. A switch comprising a horizontally pivoted arm, a mercury switch on said arm adapted to be tilted for making and breaking the circuit when the arm is rocked on its pivot, and means for rocking said arm 100

with a snap action comprising a bar pivoted concentrically with the arm, resilient means for holding said bar in a definite position, means for moving said bar against the action of the resilient means whereby when it is released it will return to its definite position, and a connection between the arm and bar including a double faced cam on one and a spring projected member on the other for engaging the double faced cam, whereby the spring projected member will be caused to ride from one face of the cam to the other with a snap action, substantially as set forth.

3. A snap switch comprising a support, a bar pivoted on said support, a resilient member maintaining said bar in one position, a connection between said bar and an electro-magnet for moving the bar against the action of the resilient means to another position, a mercury tube switch, a pivotally supported switch carrying member provided with opposed cam faces, means on the bar for engaging said cam faces, and spring means actuating said last mentioned means whereby upon the energizing and de-energizing of the electro-magnet the oscillation of the bar will cause the member engaging one of the cam faces on the switch supporting member to ride over to the other cam face and thus operate the switch, substantially as set forth.

In witness whereof, we have hereunto set our hands at Waynesboro this 20th day of April, A. D. nineteen hundred and twenty-eight.
